United States Patent Office

Des. 184,155
Patented Dec. 23, 1958

184,155

BOAT STEERING WHEEL

Clifford Brooks Stevens, Milwaukee, Wis., assignor to The Vollrath Co., Sheboygan, Wis., a corporation of Wisconsin

Application December 12, 1957, Serial No. 48,877

Term of patent 3½ years

(Cl. D71—1)

Fig. 1 is a side perspective view of a boat steering wheel showing my new design;

Fig. 2 is a top plan view thereof;

Fig. 3 is a sectional view taken on line 3—3 of Fig. 2; and

Fig. 4 is a fragmentary front view of the hub and supports of the boat steering wheel with the rim omitted.

I claim:

The ornamental design for a boat steering wheel, substantially as shown.
